METHOD OF TREATING CRESYLIC PITCH TO
OBTAIN TAR-ACIDS THEREFROM

Charles F. Winans, Borough of Beaver, Beaver County, Pa., assignor, by mesne assignments, to Koppers Company, Inc., a corporation of Delaware

Application December 18, 1942, Serial No. 469,446

3 Claims. (Cl. 260—627)

This invention relates to the treatment of a pitchy carbonaceous material, formed in tar acid recovery processes, to obtain valuable products from such material.

The particular material treated by the process of the present invention is known as "cresylic pitch." It is formed as a pitchy residue in the distillation of tar acids obtained from coal tar or other tar acid bearing oils. These oils containing tar acids are initially treated in a well-known manner with caustic alkali to form tar acid salts which are separated from the unreacted, undissolved oil. The separated tar acid salts are "sprung" by means of carbon dioxide or the equivalent, to form free tar acids. The recovered free tar acids are subjected to fractional distillation to obtain such tar acids as phenol, cresols, and xylenols.

The cresylic pitch obtained as a residue in the distillation of the recovered tar acids is a very viscous, black, tarry material of characteristic odor, and is highly complex in its chemical composition. It is difficult to handle, and, in general, it is considered a distress product, little specific use having heretofore been found for it, and accumulations thereof being somewhat of a plant nuisance.

A cresylic pitch sample was found by analysis to contain approximately 10.15% water, 9.23% ash (8.15% sodium carbonate, 0.93% iron oxide, and 0.15% other inorganic oxides such as those of aluminum and silicon) and 80.72% organic matter. Mere distillation of cresylic pitch by itself under vacuum yields only small amounts of distillate and mainly a residue of coke. In fact it is impossible to distill the pitch without excessive coking and consequent decomposition.

An object of the present invention is to provide processes for converting cresylic pitch into more readily distillable fractions yielding various valuable compounds, including particularly tar acids, and also various useful hydrocarbons. A further object is to provide a method of treating cresylic pitch under conditions favorable for the generation of tar acids from such pitch. Another object is to provide a process for cyclically treating cresylic pitch whereby relatively high yields of commercially useful products are obtained.

The invention comprises, broadly, hydrogenating cresylic pitch with or without catalyst preferably at raised temperatures and preferably at superatmospheric pressures. Before hydrogenation, the cresylic pitch may, if desired, be treated with a mineral acid, by which treatment some tar acids are rendered available. The acid treat-

ment in itself may be employed as a means of providing appreciable yields of tar acids. The acid treatment followed by hydrogenation, however, is a more highly effective method of beneficiating the cresylic pitch.

If the cresylic pitch as received from a tar acid plant is to be subjected to a preliminary acid treatment before hydrogenation, it is mixed with an excess of dilute mineral acid such as sulphuric or hydrochloric acids, thereby completely destroying the alkalinity of the cresylic pitch. The resulting mixture is washed with hot or warm water to remove the excess acid, or to render the pitch neutral, and also to remove soluble inorganic salts. The wet material is heated under reduced pressure to remove water, whereafter the material is heated in a still to about 150° C. at about 1.5 mm. to remove tar acids. A yield of about 20% to 30% tar acids is thereby obtainable.

The pretreated cresylic pitch, from which inorganic material and acid-converted products are removed, is in excellent condition for hydrogenation. Either this pretreated pitch or the raw cresylic pitch is subjected to the hydrogenation treatment described hereinbelow.

When the pitch is subjected to the action of hydrogen or of a hydrogenating gas under suitable conditions, a liquefaction of the pitch occurs, thereby furnishing a mobile liquid from which a major portion is distillable up to about 275° C. at atmospheric pressure. The distillate contains up to, or about 80% tar acids comprising phenol (C_6H_5OH), cresols, xylenols, and some higher phenolic bodies. The non-phenolic portion of the distillate comprises benzene, toluene, xylene, cyclohexane, cyclohexanol, solvent naphtha, naphthalene, and other neutral oil constituents. Fractions of the distillate boiling in a range of 200° to 250° C. also contain small proportions of tar bases such as quinoline, quinaldine, isoquinoline and others which may be separated from the said distillate. The residue left after distilling desired fractions from the beneficiated pitch may be further hydrogenated to furnish additional amounts of valuable products.

The temperature and pressures and time of treatment of cresylic pitch during hydrogenation may vary and are preferably kept within certain desirable ranges. The temperatures which have been useful are from about 300° to about 500° C. and preferably in the range of about 350° to 450° C. At 350 C. a relatively long reaction time is required to produce a desired degree of liquefaction while at 450° C. the time is considerably short-

tened. Temperatures over 450° C. may be employed, but such temperatures are less desirable for tar acid production than those of 450° C. and lower.

The pressure of hydrogen or hydrogenating gases during hydrogenation may be 500 lbs. per square inch or higher. The extent of liquefaction is increased at higher pressures, other variables remaining constant. Pressures as low as 300 lbs. per square inch may be used, or higher pressures up to 3000 lbs. per square inch or up to the limit obtainable in the apparatus in which the conversion is effected.

With increase of reaction time in batch processes there is an appreciable increase in yield. From about one half hour to about 3 hours are desirable for effecting a liquefaction of over 50% or of about 50% to 55% of the pitch.

The hydrogenation of the cresylic pitch, as indicated above, may be conducted either in the presence of or in the absence of a catalyst. In certain instances the walls of the hydrogenation chamber have some catalytic effect. The small proportion of iron oxide generally present in the pitch may also be catalytically active. Improved results are obtained when the hydrogenation is conducted in the presence of an added catalytic substance. Various types of catalytic substances are applicable such as certain metallic elements including iron, nickel, etc., and particularly molybdenum sulphide, stannous sulphide, other metallic sulphides, such as those of iron, cobalt, nickel, zinc, silver, mercury, lead, copper and tungsten. These sulphides may be used alone or with additions of halides such as iodine, or halogen compounds such as iodoform, ethylene chloride, bromoform, and the like. Molybdenum oxides, tungsten oxides, and others with or without the addition of elemental sulphur or of a compound containing sulphur may also be used. Any of the well known sulfactive catalysts and particularly those of the type which resist poisoning by sulphur are highly effective in the present hydrogenation process.

In the accompanying drawings, flow diagrams are presented which illustrate several examples of methods for beneficiating cresylic pitch. As illustrated in Figure 1 cresylic pitch is hydrogenated in a closed vessel, such as an autoclave at elevated temperatures and pressures and for a period as indicated above. After the desired liquefaction has taken place the hydrogenated cresylic pitch is subjected to distillation to remove tar acids and other compounds. The residue which remains after removal of the tar acids and other compounds generated during hydrogenation are further hydrogenated under conditions indicated above to yield additional amounts of tar acids. The tar acids are separated from the hydrogenated residue by distillation and residues from the distillation of this secondary hydrogenation product can be further treated if desired.

Owing to the fact that the residues from the distillation of the secondary hydrogenation products can be further hydrogenated, a continuous process is feasible. Such a process is illustrated in Figure 2. Cresylic pitch is hydrogenated in an autoclave which may be represented by a rectangle 1. The hydrogenated cresylic pitch is distilled in a still represented by a rectangle 2 to remove tar acids, hydrocarbons, etc. The residue from the distillation is mixed with fresh cresylic pitch and the mixture is introduced into

the autoclave 1 to be hydrogenated. A cyclic process is thus carried on and the complete utilization of the cresylic pitch is made possible.

In Figure 3, a flow diagram is shown to illustrate the pretreatment of cresylic pitch before hydrogenation. By such pretreatment a certain amount of tar acids is formed which are separated from the pretreated cresylic pitch. The remaining portion of the pretreated pitch is then hydrogenated to form further amounts of tar acids and other compounds.

During hydrogenation, vent gases from the autoclave may be passed through dilute sulphuric acid for the purpose of removing ammonia that may be present. The gases may also be condensed or they may be washed with oil to remove lighter hydrocarbons that form. Such lighter hydrocarbons have a boiling range of -4° to about 20° C.

The following examples are given by way of illustration and are not to be considered as limitations.

Example 1.—A charge of cresylic pitch in the absence of a catalyst is placed in an autoclave under an initial pressure of about 900 lbs. per square inch and heated to about 450° C. in the presence of a hydrogenating gas. The temperature is held at this point for about one hour. The apparatus is thereafter cooled to room temperature, the pressure falling to about 400 lbs. per square inch. The liquid product formed is removed from the autoclave and distilled. The distillate comprises about 3.2% water, 8.55% of materials boiling to 180° C., 44.4% distillate boiling from about 180° C. at atmospheric pressure to about 150° C. at 2 mm. pressure, and a residue of about 35.9% pitch. The above 44.4% fraction contains about 84% tar acid. This fraction is treated to remove tar acids therefrom.

Example 2.—A charge of cresylic pitch is mixed with about 1% by weight of molybdenum sulphide as catalyst. The mixture in an autoclave is submitted to an initial pressure of 900 lbs. per square inch and heated to 450° C. in the presence of a hydrogenating gas. The temperature is held at this point for about one hour. The apparatus is cooled to room temperature and the pressure is gradually reduced. The hydrogenation product is distilled. The distillate comprises about 3.2% water, 8.5% of material boiling to 180° C., about 55.3% distillate boiling from 180° at atmospheric pressure to 150° at 2 mm. pressure, and a residue of about 29.7% pitch. The 55.3% fraction is treated to obtain tar acids. This fraction contains about 82% tar acids.

Example 3.—Cresylic pitch is placed in an autoclave and submitted to an initial partial hydrogenating pressure of about 1400 lbs. per square inch and a temperature up to about 450° C. The autoclave is cooled and the liquefied product is treated to obtain free tar acids. On distillation there are obtained about 3.6% water, 8% material up to 180° C., 52.8% distillate from 180° at atmospheric pressure to 150° at 2 mm. pressure containing about 82% tar acids, and a residue of about 28.4% pitch.

Example 4.—Cresylic pitch mixed with about 1% molybdenum sulphide is hydrogenated for about one-half hour at 450° C., the initial hydrogenating pressure being about 1950 lbs. per square inch. The beneficiated pitch comprises about 3.7% water, 9% material boiling up to about 180° C., 49.6% distillate from 180° at atmospheric pressure to 150° at 2 mm. pressure

containing about 79% tar acids, and a residue of 31.3%.

Example 5.—Cresylic pitch is hydrogenated for about one hour at 400° C. in the presence of 1% molybdenum sulphide under pressure, the initial partial hydrogenating pressure being about 1950 lbs. per square inch. The hydrogenated product contains about 2.8% water, 4.5% material boiling to 180° C., 37% distillate from 180° at atmospheric pressure to 150° at 2 mm. pressure containing 85% tar acids, and 43.7% pitch residue.

Example 6.—A charge of cresylic pitch is hydrogenated at 350° C. for 5½ hours in the presence of 1% molybdenum sulphide, the initial pressure being about 1700 lbs. per square inch. The reaction product contains 2% water, 5.1% material boiling up to 180° C., 24% distillate from 180° at atmospheric pressure to 150° at 2 mm. pressure containing about 79% tar acids, and 67.1% pitch residue.

Example 7.—Cresylic pitch in the presence of about 5% nickel catalyst is hydrogenated at about 275 C. for about 2 hours, the initial pressure being 1200 lbs. per square inch. The hydrogenated material is distilled to obtain a tar acid fraction. The yield of tar acids is about 32.1%.

Example 8.—Pitch residues obtained from a number of hydrogenated cresylic pitch batches after distillation of tar acids, are combined and hydrogenated for 5½ hours at 450° C. in the presence of 1% molybdenum sulphide, the initial pressure being 1700 lbs. per square inch. The product comprises 3.8% water, 12.8% material boiling up to 180° C., 45.4% distillate from 180° at atmospheric pressure to 150° C. at 2 mm. pressure containing 41% tar acids, and 28.8% pitch residue. This residue is rehydrogenated under similar conditions. The resulting product comprises 25% water, 4.95% materials boiling up to 180 C., 37% distillate from 180° at atmospheric pressure to 150° C. at 2 mm. pressure containing 20% tar acids, and 48.8% pitch residue. The latter residue may be further hydrogenated.

In the last example the pitch residue instead of being separately hydrogenated is alternatively mixed with fresh cresylic pitch and the resultant mixture is hydrogenated. Each residue obtained thereafter is remixed with fresh batches of cresylic pitch to be hydrogenated.

Example 9.—Raw cresylic pitch is thoroughly mixed with an excess of about 10% dilute mineral acid (sulphuric acid or hydrochloric acid). The excess is beyond the amount necessary to neutralize alkalinity of the cresylic pitch. The resulting mixture is washed with warm water to remove soluble inorganic salts and excess acid. The washed pitch is subjected to vacuum distillation to remove water. It is subjected to further distillation to obtain a tar acid fraction which yields about 26% tar acids. The pitch residue remaining in the still is subjected to hydrogenation in the presence of a catalyst at about 450° C. under a partial hydrogenating pressure of over 300 lbs. per square inch for one hour either continuously or intermittently. The hydrogenated product is distilled to recover volatile products including hydrocarbons, tar acids and a residue. The distillate is treated to separate tar acids from neutral oil. About 50% of the hydrogenated product boils up to about 275° C. at atmospheric pressure. The distillate thus obtained contains about 80% tar acids.

In each of the above examples a fraction con-

taining the greater proportion of tar acids on distillation of the hydrogenated pitch, is treated in the conventional manner for obtaining free tar acids and neutral oil. For example, the tar acid fraction is mixed with sodium hydroxide to form sodium phenolates which separate out of the neutral oil in the form of a layer. The phenolate layer is then subjected to a springing treatment with carbon dioxide. The phenols are set free and may be fractionated to obtain individual phenolic compounds. From a hydrogenated cresylic pitch yielding tar acids to the extent of about 50% of the total yield of liquefied product, there is obtained the following:

	Per cent
Phenol	1.2
Cresols	23.1
Xylenols	33.1
Tar acids boiling from 220° to 240° C.	27.5
Tar acids boiling above 240° C.	15.1

Alternatively, in each of the above examples, tar acid oil produced and containing the tar acids and neutral oil is a valuable product as such. Among other uses the tar acid oil serves, for instance, as a material in the manufacture of certain insecticide oils.

By means of the process of the present invention, cresylic pitch which has heretofore been commercially valueless, is converted into products that are of considerably greater value than the pitch. The tar acids are combined with those of the tar acid plant, thereby increasing single ring tar acid production. Neutral oil and hydrocarbons obtained in the hydrogenation process are important commodities otherwise lost and now finding increased diversified application.

While certain periods of time, temperatures, and pressures are prescribed in the above examples, these factors may be so adjusted to each other that a substantial proportion of constituents in the pitch is converted into tar acid fractions distillable without decomposition.

It is apparent from the above description that various changes may be made in the procedures without departing from the spirit and scope of the invention or sacrificing all of its material advantages, the procedures hereinbefore cited by way of illustration being merely the preferred embodiments thereof.

What is claimed is:

1. In a process of producing free tar-acids from cresylic pitch residue that is non-distillable without excessive decomposition and coking, and that is formed by distillation of a distilland substantially completely consisting of chemically separated free tar-acids, which tar-acids are obtainable by reacting tar-acids in tar-acid-bearing oil with caustic alkali to form tar-acid salts, removing so-formed tar-acid salts from unreacted oil, and freeing the tar-acids from said salts in a springing operation; subjecting the said cresylic pitch residue to a pressure of over 300 pounds per square inch at a temperature in substantially the range of 300° C. to 500° C. in contact with hydrogen to effect liquefaction of material in the said cresylic pitch residue and thereby to obtain tar-acid material from which free tar-acids are distillable without decomposition, and separating free tar-acids comprising phenol, cresols and xylenols from the resulting mass.
2. In a process of producing free tar-acids from cresylic pitch residue that is non-distillable without excessive decomposition and coking, and that is formed by distillation of a distilland substan-

tially completely consisting of chemically separated free tar-acids, which tar-acids are obtainable by reacting tar-acids in tar-acid-bearing oil with caustic alkali to form tar-acid salts, removing so-formed tar-acid salts from unreacted oil, and freeing the tar-acids from said salts in a 5 springing operation; subjecting the said cresylic pitch residue to a pressure of from substantially 20 atmospheres to 200 atmospheres at a temperature in substantially the range of 300° C. to 500° C. in the presence of a catalyst and in contact with hydrogen to effect liquefaction of material in the said cresylic pitch residue and thereby to obtain tar-acid material from which free tar-acids are distillable without decomposition, and distilling free tar-acids comprising phenol, cresols and xylenols from the resulting mass.

3. In a process of producing free tar-acids from cresylic pitch residue that is non-distillable without excessive decomposition and coking, and that is formed by distillation of a distilland substantially completely consisting of chemically separated free tar-acids, which tar-acids are obtain-

able by reacting tar-acids in tar-acid-bearing oil with caustic alkali to form tar-acid salts, removing so-formed tar-acid salts from unreacted oil, and freeing the tar-acids from said salts in a 10 springing operation; contacting the said cresylic pitch residue and dilute mineral acid to acidify the mass, washing the acidified mass to remove free mineral acid therefrom; distilling the so-treated cresylic pitch residue to obtain a fraction containing free tar-acids, subjecting the resulting undistilled residual portion of the acid-treated cresylic pitch residue to a pressure of over 300 pounds per square inch at a temperature in substantially the range of 300° C. to 500° C. in contact with hydrogen to effect liquefaction of the 15 said undistilled residual portion of the acid-treated cresylic pitch residue and thereby to obtain tar-acid material from which free tar-acids are distillable without decomposition, and distilling free tar-acids comprising phenol, cresols and xylenols from the resulting said tar-acid material.

CHARLES F. WINANS.
